UNITED STATES PATENT OFFICE.

CHRISTIAN AALBORG, OF WILKINSBURG, PENNSYLVANIA, ASSIGNOR TO WESTINGHOUSE ELECTRIC AND MANUFACTURING COMPANY, A CORPORATION OF PENNSYLVANIA.

OSCILLATING FAN-MOTOR.

1,241,599.

Specification of Letters Patent.

Patented Oct. 2, 1917.

Application filed December 26, 1911. Serial No. 667,921.

To all whom it may concern:

Be it known that I, CHRISTIAN AALBORG, a citizen of the United States, and a resident of Wilkinsburg, in the county of Allegheny and State of Pennsylvania, have invented a new and useful Improvement in Oscillating Fan-Motors, of which the following is a specification.

My invention relates to oscillating fan motors and it has special reference to devices of this general class in which the oscillatory movements thereof are effected through the agency of suitable mechanisms which are operatively associated with the motor shafts.

The object of my invention is to improve and simplify the construction and operation of devices of the above-indicated character, and to provide an adequate and effective means for readily rendering the oscillating mechanism inoperative and for locking the rotatable portion of the device in any desired position.

Another object of my invention is to provide a dust-proof protective casing which may be detachably secured to the driving motor for the purpose of inclosing all movable parts of the oscillating mechanism.

In the accompanying drawings, Figure 1 is a view, partially in side elevation, and partially in section, of a device constructed in accordance with my invention. Fig. 2 is plan view, partially in section, of a portion of the device shown in Fig. 1, and Fig. 3 is a bottom plan view of a portion of the operating mechanism.

Referring to the drawings in detail, a motor 1 of any well known construction, is pivotally mounted on a supporting base 2 by means of an adjustable hinge or coupling 3, in such manner that the device is adapted for either desk or wall mounting and for any desired operating position.

The armature shaft 4 of motor 1 is mounted at its respective ends in suitable bearing members 5 and 6, one end of the shaft 4 being provided with a plurality of fan blades 7 which are inclosed and protected from contact with exterior objects by means of a suitable cage or guard 8. The opposite end 9 of the shaft 4 is provided with a tongue portion 10 which is adapted to co-operate with a suitable slot 11 in one end of a worm member 12 which is co-axially disposed with

respect to the armature shaft 4 and is mounted in a bearing sleeve 6. A worm wheel 13 engages the worm member 12 in a well known manner, whereby rotative movement is imparted to a shaft 14 upon the upper end of which the wheel 13 is secured. The lower end of the shaft 14 is provided with a pinion 15 which meshes with a gear wheel 16. The gear wheel 16 is operatively associated with a portion 17 of the supporting base 2 above the coupling 3 by means of a connecting rod 18, one end of which is eccentrically pinned to the gear wheel 16 by a pin 19, while the other end thereof is attached to the aforesaid portion 17 of the supporting base 2 by a pin 20. All of the component parts of the operating mechanism hereinbefore described are effectively inclosed and protected from external injury by a dust-proof casing 21, so that no moving parts are exposed.

The casing 21 comprises the bearing sleeve 6 that terminates in an annular flange 30. The flange 30 is provided with a reduced portion 31 that is received in an opening 32 provided in the rear bearing bracket 33 of the motor 1. The casing 21 further comprises a cylindrical portion 34 that is disposed substantially at right angles to the sleeve 6, within which the shaft 14 is located. The portion 34 terminates in a hollow base portion 35 within which is located the connecting rod 18 and the gear members 15 and 16. The base portion 35 is provided, at its end, with an opening 36 through which projects a portion 37^a of a pivot pin 37, the upper end of which portion 37^a is headed over so as to fixedly position the pin 37, with respect to the base portion 35 of the casing 21. The pin 37 therefore is carried by the base portion 35 and is entirely independent of the motor casing 38.

The upper part of the portion 35 is provided with upwardly and outwardly curved members 35^a, the back one of which is shown in dotted lines in Fig. 1, and said members 35^a constitute a sort of saddle to receive and support the motor casing 38. A cover 39 is secured to the base portion 35, thereby entirely inclosing the connecting rod 18 and its gearing. From the foregoing, it is apparent that the component parts of the oscillating mechanism may be completely assembled within the casing 21 and then ap-

plied, as a unit, to any fan motor, the shaft of which has been previously provided with a tongue portion, such as shown at 10. When it is desired to remove or to replace 5 the motor, it is only necessary to remove the means that secure the portion 35 to the motor casing 38 and then withdraw the motor shaft 4 from the worm 12.

The particular operating mechanism set 10 forth forms no material part of my present invention, except as it serves to complete a useful combination of elements by means of which the rotational movement of the armature shaft 4 is transmitted to the gear 15 wheel 16 and an oscillatory movement of the fan is thereby obtained, in a well known manner.

Referring now particularly to Fig. 2, the outer end of the worm member 12 is provided 20 with a transverse slot 22 having inclined sides 23, and said slot is adapted to receive a frusto-conical portion 24 which forms an integral part of a pin or rod 25, the outer end 26 thereof being riveted or 25 otherwise suitably secured to an adjustable cap member 27. The cap member 27 is screw-threaded upon a neck portion 28 of a bushing 29, which is rigidly secured to the outer end of the bearing member 6 in a suitable 30 manner.

Assuming that the fan motor is in operation and that the various parts thereof occupy the positions shown in the drawings, the oscillating mechanism may be rendered inoperative and the fan motor adjusted and locked in any desired position merely by unscrewing the cap member 27, thereby drawing the worm member 12 in a longitudinal direction out of engagement with 35 the tongue portion 10 at the end of the motor shaft 4. Thus, the oscillating mechanism is disengaged from the shaft 4 of the driving motor 1 and the fan continues to operate in a fixed position relative to its 40 supporting base. Furthermore, the fan is held or locked in this position by reason of the coöperative engagement of the worm member 12 and worm wheel 13, it being well understood by those skilled in the art, that 45 this class of gearing cannot be operated in a reverse direction.

In order to resume the oscillatory movement, the cap member 27 is screwed upon the bushing 29 until the tongue and slot 50 connection between the motor shaft 4 and the worm member 12 is again effected.

Obviously, various other devices for rendering the oscillating mechanism ineffective and for locking the fan motor in any desired 55 position may be employed, and many modifications in the structural details and in the arrangement and location of parts may be effected without departing from the spirit and scope of my invention.

I claim as my invention:

1. In a revoluble motor-driven fan, the combination with an armature shaft and operating means normally coupled thereto for effecting an oscillatory movement of said fan, of means for uncoupling said operating means from said shaft and locking said fan in position.

2. In a revoluble motor-driven fan, the combination with an armature shaft and mechanical means normally coupled thereto for effecting an oscillatory movement of said fan, of means for uncoupling said mechanical means from said shaft and means, including a part of the aforesaid means, for retaining the said fan in position when the said parts are uncoupled.

3. In a revoluble motor-driven fan, the combination with an armature shaft, a worm member normally coupled to the end of said shaft and mechanical operating means coöperating with said worm member for imparting an oscillatory movement to said fan, of manually operated means associated with said worm member for uncoupling said member from said shaft and locking the said fan in position.

4. In a revoluble motor-driven fan, the combination with an armature shaft and mechanical means normally coupled thereto for effecting an oscillatory movement of said fan, of means for uncoupling said mechanical means from said shaft and means, including a part of the aforesaid means, for restraining further oscillatory movement of said fan when the said parts are uncoupled.

5. In a revoluble motor-driven fan, the combination with a rotatable armature shaft, a worm member having a tongue and slot connection with the end of said shaft, and mechanical means associated with said worm member for imparting an oscillatory movement to said fan, of relatively stationary means having a loose connection to said worm member for effecting a longitudinal movement thereof, whereby said member is disengaged from said shaft.

6. In a revoluble motor-driven fan, the combination with an armature shaft and mechanical means coöperating therewith for effecting an oscillatory movement of said fan, of means for rendering said mechanical means inoperative and locking said fan in position.

7. In a revoluble motor-driven fan, the combination with an armature shaft and mechanical means normally in engagement therewith for effecting an oscillatory movement of said fan, of means for disengaging said mechanical means from said shaft and for restraining further oscillatory movement of said fan when said parts are disengaged.

8. In a revoluble motor driven fan, the combination with an electric motor having a rotatable shaft, a worm detachably secured to an end of said shaft and having a recess 5 in the free end thereof, and a mechanism operatively connected to said worm for oscillating said fan, of a member disposed coaxially with said worm and having one end disposed within said recess, and a manually 10 adjustable cap secured to the other end of said member and adapted to disconnect said worm and said shaft.
9. In a revoluble motor-driven fan, the combination with a supporting base, an electric motor pivotally mounted thereon and having a rotatable armature shaft, a worm 15 loosely coupled to an end of said shaft, a worm-wheel driven thereby and mounted on an auxiliary shaft, a driving-rod eccentrically connected at one end to said auxiliary shaft and secured at the other end to said 20 supporting base for effecting an oscillatory movement of said fan upon said base, of a casing for supporting said gearing and said auxiliary shaft and for inclosing said driving rod, the said casing being detachably secured to said motor whereby said oscillating mechanism may be removed from said 25 motor as a unit.
10. In a revoluble motor-driven fan, the combination with a supporting base, an electric motor pivotally mounted thereon and having a rotatable armature shaft, a worm 30 loosely coupled to an end of said shaft; a worm-wheel driven thereby and mounted on an auxiliary shaft, a driving-rod eccentrically connected at one end to said auxiliary shaft and secured at the other end to said 35 supporting base for effecting an oscillatory movement of said fan upon said base, of a casing detachably secured to said motor for supporting said gearing and said auxiliary shaft and for inclosing said driving rod.
11. In a revoluble motor-driven fan, the combination with a supporting base, an electric motor pivotally mounted thereon and having a rotatable armature shaft, and mechanical means embodying reduction gearing 40 loosely coupled to said shaft, an auxiliary shaft driven thereby and a driving rod connected between said shaft and said supporting base for effecting an oscillatory movement of said fan upon said base, of a protecting casing secured to said motor and serving to inclose and support all movable parts of said mechanical means.
12. In a revoluble motor-driven fan, the combination with a supporting base, an electric motor pivotally mounted thereon and having a rotatable armature shaft, a worm 45 loosely coupled to an end of said shaft, a worm wheel driven thereby and mounted on an auxiliary shaft, a driving-rod eccentrically connected at one end to said auxiliary shaft and secured at the other end to said 50 supporting base for effecting an oscillatory movement of said fan upon said base, of a casing for inclosing all movable parts of said mechanical means.
13. In a revoluble motor-driven fan, the combination with a supporting base, an electric motor pivotally mounted thereon and having a rotatable armature shaft, a worm 55 loosely coupled to an end of said shaft, a worm wheel driven thereby and mounted on an auxiliary shaft, a driving-rod eccentrically connected at one end to said auxiliary shaft and secured at the other end to said 60 supporting base for effecting an oscillatory movement of said fan upon said base, of a casing for inclosing and supporting said gearing, said auxiliary shaft and said driving rod, whereby said oscillating mechanism 65 may be applied to said motor as a unit.
14. In a revoluble motor-driven fan, the combination with a supporting base, an electric motor pivotally mounted thereon and having a rotatable armature shaft, and mechanical means embodying reduction gearing 70 loosely coupled to said shaft, an auxiliary shaft driven thereby and a driving rod connected between said shaft and said supporting base for effecting an oscillatory movement of said fan upon said base, of a protecting casing secured to said motor and serving to inclose and support said gearing, said auxiliary shaft and said driving rod.
15. In a revoluble motor-driven fan, the combination with a supporting base, an electric motor pivotally mounted thereon and having a rotatable armature shaft, and mechanical means embodying reduction gearing 75 loosely coupled to said shaft, an auxiliary shaft driven thereby and a driving rod connected between said shaft and said supporting base for effecting an oscillatory movement of said fan upon said base, of a protecting casing secured to said motor and serving to inclose and support said gearing, said auxiliary shaft and said driving rod.
16. In a revoluble motor-driven fan, the combination with a supporting base, an electric motor pivotally mounted thereon and having a rotatable armature shaft, and mechanical means embodying reduction gearing 80 loosely coupled to said shaft, an auxiliary shaft driven thereby and a driving rod connected between said shaft and said supporting base for effecting an oscillatory movement of said fan upon said base, of a protecting casing secured to said motor and serving to inclose and support said gearing, said auxiliary shaft and said driving rod.
17. In a revoluble motor-driven fan, the combination with a supporting base, an electric motor pivotally mounted thereon and having a rotatable armature shaft, and mechanical means embodying reduction gearing 85 loosely coupled to said shaft, an auxiliary shaft driven thereby and a driving rod connected between said shaft and said supporting base for effecting an oscillatory movement of said fan upon said base, of a protecting casing secured to said motor and serving to inclose and support all movable parts of said mechanical means.
18. In a revoluble motor-driven fan, the combination with a supporting base, an electric motor pivotally mounted thereon and having a rotatable armature shaft, and mechanical means embodying reduction gearing 90 loosely coupled to said shaft, an auxiliary shaft driven thereby and a driving rod connected between said shaft and said supporting base for effecting an oscillatory movement of said fan upon said base, of a protecting casing secured to said motor and serving to inclose and support all movable parts of said mechanical means.
19. In a revoluble motor-driven fan, the combination with a supporting base, an electric motor pivotally mounted thereon and having a rotatable armature shaft, and mechanical means embodying reduction gearing 95 loosely coupled to said shaft, an auxiliary shaft driven thereby and a driving rod connected between said shaft and said supporting base for effecting an oscillatory movement of said fan upon said base, of a protecting casing secured to said motor and serving to inclose and support all movable parts of said mechanical means.

In testimony whereof, I have hereunto subscribed my name this 12th day of Dec., 1911.

CHRISTIAN AALBORG.
